BED JACKET

John R. Collier, Mount Ida, Ark.

Application October 31, 1952, Serial No. 318,045

1 Claim. (Cl. 2—108)

1

The invention relates to bed jackets and more particularly to a jacket designed to cover the shoulders, arms and chest of a person sitting up in bed.

It is among the objects of the invention to provide an improved bed jacket which is suitable for wear by either men or women, and effectively covers and protects the shoulders, arms and chest of a person reclining in bed with the upper portion of the body in a raised position for reading or other activities; which opens in the back where the body is protected by the bedding on which the wearer reclines and has a continuous front for covering the chest of the wearer and long sleeves for covering the wearer's arms; which has a length such that its lower portion is retained under the upper portions of the bed covers; which is comfortable to wear and provides full freedom of the wearer's arms; which is easy to put on and take off while reclining in bed; and which is simple and durable in construction, economical to manufacture, and neat and attractive in appearance.

Other objects and advantages will become apparent from a consideration of the following description and the appended claim in conjunction with the accompanying drawing wherein:

Figure 1 is a front elevational view of a bed jacket illustrative of the invention;

Figure 2 is a back elevational view of the jacket illustrated in Figure 1; and

Figure 3 is an elevational view of an end portion of one of the jacket sleeves with portions broken away to illustrate the construction of the sleeve.

With continued reference to the drawing, the bed jacket is preferably formed of a heavy fabric material providing adequate warmth for the person wearing the jacket, and includes a body portion, generally indicated at 10, the front 11 of which is continuous to extend across the chest of the wearer and the back of which is discontinuous providing two separated back parts 12 and 13, having convexly curved opposed edges, as indicated at 14 and 15 respectively. The bottom edge of the front part 11 of the jacket body portion is preferably substantially straight, as indicated at 16, and provided with a stitched hem 17 and the top edge is provided with a rounded notch or opening 18 constituting the front part of the neck opening of the jacket. The curved edge of the notch 18 is continuous with the curved edges 14 and 15 of the back parts 12 and 13 of the jacket, so that the curved inner edge of the jacket extends around the throat of

2

the wearer, over the shoulders and downwardly along the back. The opposed edges 14 and 15 of the back part of the jacket are preferably separated for increased comfort and facility in putting the jacket on and taking it off, the space between these edges being overlapped by the bedding on which the wearer reclines, so that the wearer's back is not exposed.

The body portion 10 is provided with sleeve openings 19 and 20, one in each side thereof and extending to the top portion of the jacket body, which extend over the shoulders of the wearer and long sleeves 21 and 22 are attached at their inner ends to the body portion 10, one at each side of the body portion and in surrounding relationship to the corresponding sleeve openings 19 and 20.

At their outer ends the sleeves are hemmed to provide two or more thicknesses of material at the outer ends of the sleeves, and elastic bands, as indicated at 23 in Figure 3, encircle the sleeves near the outer ends thereof to bind the sleeves tightly about the wrists of the wearer, these elastic bands being disposed between the several layers or thicknesses of material at the hemmed, outer ends of the sleeves.

A pocket 24 is mounted on the front part of the body portion 10 of the jacket between the top and bottom edges of the front part and to one side of the center of the front part to contain small articles for the convenience of the wearer of the jacket.

The body portion 10 of the jacket, in addition to being hemmed along its bottom edge, as indicated at 17, is also hemmed along the curved edges of the back parts 12 and 13 and along the curved edge 18 of the neck opening, as indicated at 25, so that the jacket, while simple in construction, has adequate structural strength to continue in use for a long period of time.

The invention may be embodied in other specific forms without departing from the spirit or essential characteristics thereof. The present embodiment is, therefore, to be considered in all respects as illustrative and not restrictive, the scope of the invention being indicated by the appended claim rather than by the foregoing description, and all changes which come within the meaning and range of equivalency of the claim are, therefore, intended to be embraced therein.

What is claimed is:

A bed jacket comprising a body portion continuous in the front and discontinuous in the back thereof and provided with sleeve openings

one in each side above the bottom thereof, and long sleeves attached at their inner ends to said body portion one at each end of the latter and in surrounding relationship to the corresponding sleeve openings, the front of said body portion having a concavely curved top edge providing the front portion of a neck opening and the ends of said body portion at the back of the jacket each having a width less than one-half the width of said front portion and having convexly curved 10 edges continuous with the concavely curved edge of said neck opening.
